UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,688, dated March 18, 1880.

Application filed February 16, 1880. Term of patent 3½ years.

To all whom it may concern:

Be it known, that we, SIMON HEITER and SALOMON J. LESEM, citizens of the United States, both residing at New York, in the county and State of New York, have invented and produced a new and original Design for Umbrella or Parasol Handles, of which the following is a specification, reference being had to the accompanying drawing, forming part thereof.

Our object is to produce a new and attractive design for the head of an umbrella or parasol handle; and the design consists in a scroll-like ornamentation on the top of such handle, as will be hereinafter described.

The accompanying drawing represents, in a side view, our newly-designed handle. *a* is the straight portion of the handle. At the top the handle expands into two divergent branches or arms, *b b*, slightly curved, and terminating in rounded tips. Between and at the base of the branches is a bead-like embossment, *c*. On the branches *b b* rests a double scroll-like ornamentation, *d*, which consists of the plain rounded portion *d'*, with reverse scroll ends *e e'*, the end *e* coiling inward and

downward, and the end *e'* outward and upward, the scroll ends resting on the tips of the branches *b b*, and the whole configuration forming a fanciful and unique design for the head of the handle.

On the top of the portion *a* of the handle is a band or ring, *f*, either plain or embossed, and of silvered or gilt metal, as desired, to add to the beauty of the design.

What we claim as new, and desire to secure by Letters Patent, is—

1. The design for an umbrella or parasol handle herein shown and described, the same consisting of the branched head *b b* and scroll-like ornamentation *d* resting thereon.

2. The design for an umbrella or parasol handle, consisting of the branches *b b*, central ornament, *c*, scroll-ornament *d*, and band or ring *f*, as shown in the accompanying drawing.

SIMON HEITER.
SALOMON J. LESEM.
